UNITED STATES PATENT OFFICE.

HUGH G. DUGAN, OF ST. LOUIS, MISSOURI.

WASHING MACHINE.

Application filed September 7, 1928. Serial No. 133,750.

This invention relates to washing mechanism which may be readily associated with or removed from a wash tub or the like, and in particular to the means provided for 5 movably supporting the mechanism in operative relation with respect to the wash tub, and permitting it to be moved on a trackway from one tub to the adjoining tub, so that one of the tubs may be used as a washing tub and the other as a rinsing tub, and the mechanism readily shifted in such a way as to conveniently operate upon clothes or other articles being washed in either of the tubs.

15 In particular, the invention relates to the means provided for suspending the washing elements from the main frame in such a way as to permit them to be readily swung up into an elevated position to permit the travel 20 of the mechanism along the track without interference from the partition wall between the two tubs, so that the mechanism as a whole can be conveniently shifted along the trackway without bodily lifting it therefrom 25 in order to pass a partition between the tubs.

Further objects and details will appear from a description of the invention in conjunction with the accompanying drawing wherein—

30 Figure 1 is a cross sectional elevation of a wash tub with the mechanism in operating position; and

35 Fig. 2 is a longitudinal sectional elevation of a tub showing the mechanism in end elevation and lifted to clear a partition wall in the tub structure.

The mechanism comprises a platform 10 which is provided on its under side with inner and outer journal brackets 11 and 12 respectively, which brackets are journaled upon 40 an inwardly extending supporting rod 13 which is carried by an elbow shaped main frame casting 14, the lower leg 15 of which has depending therefrom a guide rod 16 constituting in effect an extended portion of 45 the frame and carrying a grooved roller 17 at its lower end, which roller engages the inner edge of a lower trackway 18, suitably mounted on brackets 19 secured to the 50 legs 20 of a wash tub 21 with which the mechanism is associated.

The main frame casting is also provided with laterally extending arms 22—22, each of which journals a roller 23, which rollers 55 run upon an upper trackway 24 supported

upon the forward edge of the tub structure, the arrangement being such that the upper rollers 23 will support the weight of the washing mechanism carried by the platform 60 10, and the lower roller by its engagement with the lower trackway will counteract the weight of the parts and maintain them in overhanging relation to the tub.

As shown, the inner journal bracket 11 bears against the outer end of the upper 65 leg of the elbow shaped main casting, and the parts are arranged to permit the rocking of the platform on the journal rod 13 against the tension of a coil spring 25, which encircles the journal rod and has one of its 70 ends entered into the platform and the other entered into the journal rod.

In order to hold the platform normally in horizontal position, a latch rod 26, or equivalent mechanism, is provided. As 75 shown, the latch rod is guided through a lug 27 and the inner end of the latch rod is positioned, when the platform is level, to engage with a notch or recess 28 in the inner journal bracket 11, which engagement 80 will serve to lock the parts against rotation on the journal rod. The rear end of the latch rod is pivoted to the upper end of a trigger 29 having a center lug 30 which is pivoted upon the main frame casting, and 85 the free end of the trigger is forced outwardly by an interposed spring 31, the arrangement being such that a depression of the free end of the trigger will cause a retraction of the latch rod and a release of the 90 parts which are then free to rotate upon the journal rod.

The platform 10 serves as a mounting for the mechanisms now to be described. The platform directly supports a wringer 32 of 95 any approved construction, and also at its inner end provides a support on its upper side for a motor standard 33 and also provides a support on its lower side for a depending hanger bracket 34, which latter is 100 preferably forked at its lower end 35 as shown in Fig. 1 to afford a journal mounting for the trunnions 36 of a walking beam 37, which at its ends carries the dasher cups 38 which, as shown, are of inverted 105 ovate formation with their longer diameters in parallel relation to the journal rod 13. Although but two cups are shown, it is obvious that the number of cups might be duplicated or increased, and the configura- 110

tion of the operating parts correspondingly modified without departing from the spirit of the invention.

One of the trunnions for the walking beam 5 has secured thereto a crank arm 39 which is engaged by a pitman 40, which in turn is pivoted upon a short rotating arm 41, driven by gearing 42 actuated by a pulley 43 suitably entrained with a motor 44 which is mounted 10 upon the upper end of the standard 33. The arm 41 being shorter than the crank 39 will transform a rotary motion into an oscillating motion, which will be imparted to the dashers through the walking beam upon which they 15 are carried. Clutch elements 45 are provided for driving the wringer by the motor, and the pitman 40 is preferably made removable at its upper end to disable the dasher elements if desired when the wringer is being used.

20 In use, with the parts in position indicated in Fig. 1, the motor will be operated and the dasher elements oscillated at a point within the interior of the tub. With the parts in this position, the latch mechanism will be in 25 locked relation, so that the platform will be held horizontally and its tendency to tilt inwardly will be counteracted by engagement of the lower roller with the lower track. It is preferred to provide the upper track with 30 notches or recesses 46 so as to hold the upper rollers against longitudinal travel along the upper trackway save when the mechanism is being shifted from one tub to another.

When it is desired to shift the mechanism, 35 the trigger is actuated to release the latch after which the operating parts may be tilted to a substantially horizontal position, as in Fig. 2, and this will lift the dasher elements sufficiently to clear the partition wall 47 40 which separates the tub sections. Thereafter the mechanism can be rolled along on the trackways until the upper rollers drop into the appropriate notches 46 whereupon the parts will be restored to normal operative position, and the washing operation continued 45 in the second tub. Obviously, any number of tub sections may be provided, and the trackways extended to the required length to accommodate all of the tub sections.

50 It is preferred to so tension the spring 25 that it will act to compensate the greater weight of the motor and wringer and hold the parts, when released, in such relation as to permit the washing elements to clear the 55 tub partition, that is to say, with the platform in substantially vertical relation with respect to the journal rod upon which it is mounted, by thus compensating for the preponderant weight of the upper portion of the mechanism, the operator will be relieved from the 60 necessity of carefully steadyng the mechanism against the tendency to over tilt or upset during the shifting operation.

The mechanism, when desired, can be bodily removed from the top structure by rolling

the same to the limits of the trackways, and the trackway arrangement is one which does not materially interfere with the use of the tubs for hand washing or the like, and by making the mechanism easily removable, it 70 may be stored away when the tubs are not in use.

Although the mechanism has been described in considerable detail, it is not the intention to limit the invention, unless otherwise indicated in the claims, to the precise details shown, since the same may be modified to a considerable extent without departing from the spirit of the invention. 75

I claim:

1. In a washing machine in combination with a tub provided with a trackway thereon, a frame mounted to travel along said trackway and provided with an inwardly transversely extending journal rod overhanging 85 the interior of said tub, a supporting member journaled upon said rod and tiltable thereon, washing elements carried by said supporting member and adapted to be moved from a depending operative position to an elevated inoperative position, and means for locking said supporting member in operatively adjusted relation, substantially as described. 90

2. In a washing machine in combination with a tub provided with parallel upper and lower tracks, a main frame provided with a roller supported upon the upper edge of the upper track and a roller supported upon the inner edge of the lower track, said frame being provided with an inwardly extending 95 journal rod extending transversely of the tracks, and washer elements tiltably mounted on said rod as an axis, substantially as described. 100

3. In a washing machine in combination with a tub provided with parallel upper and lower tracks, a main frame provided with a roller supported upon the upper edge of the upper track and a roller supported upon the inner edge of the lower track, said frame being provided with an inwardly extending journal rod extending transversely of the tracks, washer elements tiltably mounted on 105 said rod as an axis, said washer elements including a frame adapted when operatively adjusted to extend down within the interior of the tub, and dasher elements carried by said frame, substantially as described. 110

4. In a washing machine in combination with a tub having upper and lower trackways, a main frame provided with a roller bearing upon the upper edge of the upper trackway, and a roller bearing upon the inner edge of the lower trackway, said main frame being provided with an inwardly extending journal rod extending transversely of the tracks, a platform journaled upon said rod as an axis and adapted to be tilted from a normal horizontal position to an inoperative angular position, a hanger depending 120 125 130

- from said platform, washing elements carried by said hanger, a motor supported upon the opposite side of said platform, an operative connection between said motor and said 5 washing elements, and a lock for normally holding the platform in operative relation, substantially as described.
5. In a washing machine in combination with a tub having upper and lower trackways, 10 a main frame provided with a roller bearing upon the upper edge of the upper trackway, and a roller bearing upon the inner edge of the lower trackway, said main frame being provided with an inwardly extending 15 journal rod, a platform journaled upon said rod adapted to be tilted from a normal horizontal position to an inoperative angular position, a hanger depending from said platform, washing elements carried by said hanger, a motor supported upon the opposite side of said platform, an operative connection 20 between said motor and said washing elements, a lock for normally holding the platform in operative relation, and a spring for 25 compensating the preponderant weight of the motor when the parts are unlocked and tilted, substantially as described.
6. In a washing machine, the combination of a tub having front and rear sides, two separated parallel trackways adjacent and parallel with the same side of the tub, one being located near the upper edge of the front wall of the tub and the other being located more distantly from said front edge, a frame located 30 above the interior of the tub and having an element extending away from the frame and spanning the space between the two trackways, a member carried by said frame and bearing downwardly upon the trackway most 35 nearly adjacent the upper edge of the front wall of the tub for supporting the weight of the frame and parts carried thereby, a member carried by the extended element and bearing against the more distant trackway 40 on that side thereof which faces toward the tub wall for preventing down tilting of the frame under the weight carried thereby, the frame being unsupported from the rear side 45 of the tub, and washing elements carried by the frame, substantially as described.
7. In a washing machine, the combination of a tub having front and rear sides, two sep- 50 arated parallel trackways adjacent and parallel with the same side of the tub, one being located near the upper edge of the front wall of the tub and the other being located more distantly from said front edge, a frame located above the interior of the tub and having an element extending away from the frame and spanning the space between the two trackways, a member carried by said frame and bearing downwardly upon the trackway most nearly adjacent the upper edge of the front wall of the tub for supporting the weight of the frame and parts carried thereby, a member carried by the extended element and bearing against the more distant trackway on that side thereof which faces toward the tub wall for preventing down tilting of the frame under the weight carried thereby, the frame being unsupported from the rear side of the tub, and washing elements carried by the frame, substantially as described.
8. In a washing machine, the combination of a tub having front and rear sides, two separated parallel trackways adjacent and parallel with the same side of the tub, one being located near the upper edge of the front wall of the tub, and the other being located at a point substantially below the upper edge of the front wall of the tub, a frame located above the interior of the tub and having an element extending away from the frame and spanning the space between the two trackways, a member carried by said frame and bearing downwardly upon the trackway most nearly adjacent the upper edge of the front wall of the tub for supporting the weight of the frame and parts carried thereby, a member carried by the extension and bearing against the more distant trackway on that side thereof which faces inwardly toward the tub wall for preventing down tilting of the frame under the weight carried thereby, the frame being unsupported from the rear side of the tub, and washing elements carried by the frame, substantially as described.

HUGH G. DUGAN.
